UNITED STATES PATENT OFFICE

143,005

DESIGN FOR A CHAIR

Edgar H. Hunter, Cambridge, Mass.

Application May 29, 1945, Serial No. 119,788

Term of patent 3½ years

(Cl. D15—1)

To all whom it may concern:

Be it known that I, Edgar H. Hunter, a citizen of the United States of America and a resident of Cambridge, in the county of Middlesex, Commonwealth of Massachusetts, have invented a new, original, and ornamental Design for Chairs, of which the following is a specification, reference being had to the accompanying drawing, forming part thereof.

In said drawing:

Fig. 1 is a perspective view of a chair showing my new design, the chair being viewed from the front thereof.

Fig. 2 is another perspective view of the same chair viewed from the back.

I claim:

The ornamental design for a chair, substantially as shown.

EDGAR H. HUNTER.
